UNITED STATES PATENT OFFICE.

SYDNEY G. MITCHINSON, OF MASSILLON, OHIO.

REVERSING-GEARING MECHANISM FOR STRAW STACKERS.

Application filed May 22, 1922. Serial No. 562,642.

This invention relates to pneumatic straw stackers and more particularly to an improvement in the means for oscillating and automatically reversing the stacker tube of a 5 pneumatic straw stacker such as is generally used upon a threshing machine.

The objects of the invention are to provide a simple and efficient means for automatically oscillating the stacker tube and for automatically reversing the movement of the tube at predetermined intervals, the stacker tube being operated from the driving means of the threshing machine, means being provided for disconnecting the driving means from the 15 stacker tube operating means.

With a construction of this kind, the stacker tube may be continuously oscillated through any desired portion of a circle in order to stack the straw evenly over a greater 20 territory than is possible with the stationary stacker tube.

The above and other objects may be accomplished with a construction such as illustrated in the accompanying drawings, in 25 which—

Figure 1 is a fragmentary plan view partly in section, of a portion of the stacker tube and the means for oscillating the same;

Fig. 2, a side elevation of the operating 30 means; and

Fig. 3, a vertical sectional view of a portion of the master gear and stacker tube.

Similar numerals refer to similar parts throughout the drawings.

35 A portion of the usual platform 1 projects from the frame of a threshing machine or similar separating implement as indicated at 1, the usual upwardly directed spout 2, through which the straw and husks pass 40 from the casing to the stacker tube, being extended upward through an opening 3 in said platform.

The stacker tube 4 may be of any usual and well known construction and is carried upon 45 the master gear 5 which is preferably a worm gear as illustrated, said gear being journaled above the platform 1 and concentric with the discharge spout 2, a central opening 6 in the gear receiving the upper end portion of the gear receiving the upper end portion of the 50 discharge spout. The stacker tube is connected to the gear 5 as by the flanged ring 7 and registers with the opening 6 in said gear.

A bracket plate 8 is connected to one edge 55 of the platform 1 and depends therefrom and has journaled therein the shaft 9 upon which is mounted the drive pulley 10 from which

power may be obtained as by a belt connected to the driving mechanism of the threshing machine.

A worm 12 is fixed upon the shaft 9 and 60 engages the worm gear 13 fixed upon the tubular shaft 14 as by the set screw 15, said tubular shaft being journaled in the bearing arms 16 and 17 formed upon the plate 8, the gear 13 engaging the outer face of the arm 16 65 and a collar 19 fixed upon the other end of the tubular shaft engaging the outer face of the arm 17, thus preventing longitudinal movement of the tubular shaft 14.

A shaft 20 is slidably mounted within the 70 tubular shaft 14 and is fixed for rotation therewith by means of the transverse pin 21 which is located through the shaft 20 and extends through the elongated slots 22 in the tubular shaft, the extremities of the pin being fixed in the double ended clutch member 23 which is thus mounted for rotation with the tubular shaft and the shaft 20, and arranged to slide with the inner shaft upon the tubular shaft.

75 The double clutch member 23 is provided at opposite ends with the clutch faces 24 arranged to mesh with the corresponding clutch faces 25 upon the bevel pinions 26 and 27 which are loosely mounted upon the tubular shaft adjacent to the bearing arms 16 and 17 respectively.

80 A beveled gear 28 is constantly in mesh with both of the bevel pinions 26 and 27, said gear being fixed upon a shaft 29 journaled in a suitable bearing 30 formed in the plate 8, and extending inwardly through said plate above the level of the platform 1 and having a clutch member 31 fixed upon its inner end.

85 The worm shaft 32 is journaled in bearings 33 upon the platform 1 and held against longitudinal movement by means of the fixed collars 34 engaging said bearings. A clutch member 35 is splined upon the shaft 32 and arranged to be normally held in engagement 90 with the clutch member 31 as by the coil spring 36, a link 37 being connected to said sliding clutch member and provided with a handle 38 or the like by means of which the clutch member may be operated to disconnect the shaft 32 when desired.

95 A worm 39 is fixed upon the shaft 32 and meshes with the worm gear 5. The gear 5 is provided near its periphery with the spaced apertures 40 into which a pair of pins, one of 100 which is shown at 41 in Fig. 1, may be selectively inserted.

These pins are arranged to alternately engage opposite sides of the trip lever 42 which is pivoted as at 43 upon the plate 8. This trip lever is provided with a slot 44 through which the shaft 20 extends, spaced collars 45 and 45^a being fixed upon said shaft and arranged to be alternately engaged by the trip lever.

The lower end of the trip lever is provided with a wrist pin 46 through which a rod 47 extends, said rod being pivoted at its lower end as at 48 to a bracket 49 upon the plate 8, and provided near the pivotal point with a shoulder or collar 50, a coil spring 51 being interposed between said collar and the washer 52, which is held in engagement with the wrist pin by means of said spring.

The operation of the device is as follows: assuming the members to be in the position shown in Figs. 1 and 2, the double clutch 24 is shown engaging the clutch member of the bevel pinion 26, the trip lever 42 having just been moved into the present position by the engagement of the pin 41 therewith, the trip lever being thrown against the collar 45, 25 sliding the shaft 20 outward and drawing the double ended clutch 24 out of engagement with the pinion 27 and into engagement with the pinion 26, reversing the direction of movement of the gear 28 and through the worm 39 30 reversing the movement of the gear 5 which carries the stacker tube.

The gear 5 will then travel in this direction, oscillating the stacker tube until the other pin 41 engages the opposite side of the trip lever 42, throwing the trip lever into engagement with the collar 45^a, sliding the shaft 20 inward and moving the clutch 24 out of engagement with the pinion 26 and into engagement with the pinion 27, reversing the direction of rotation of the gear 28, and through the worm 39 reversing the direction of the gear 5. The spring 51 and rod 47 will quickly throw the trip lever over center and hold it in this position until the lever is again engaged by one 45 of the pins 41 and reversed.

This oscillation of the stacker tube will continue automatically during the time that the threshing machine is operated, unless it is desired to hold the stacker tube at any one 50 place for a time when the clutch 35 may be disengaged, stopping the rotation of the worm 39.

I claim:—

1. In a reversing gearing for a straw tube 55 or the like having a wheel forming the pivotal support thereof, a bracket plate mounted adjacent to said wheel, a drive shaft journaled

in said plate, a worm upon the drive shaft, a beveled gear operatively connected to said wheel and journaled in the bracket plate, 60 spaced bearing arms upon the bracket plate, a tubular shaft located at right angles to the axis of said beveled gear, and journaled in said bearing arms, a worm wheel upon said tubular shaft meshing with said worm, a pair of beveled pinions loosely mounted upon said tubular shaft and meshing with said beveled gear, a solid shaft slidably mounted within the tubular shaft, said tubular shaft being slotted, a double clutch member slidably 70 mounted upon the tubular shaft, a radial pin connecting the solid shaft and double clutch member, the tubular shaft being thus continuously driven, in one direction, spaced collars upon the solid shaft, a spring toggle trip 75 lever arranged to engage each of said collars, pins upon the wheel for alternately throwing the trip lever into engagement with each collar for sliding the solid shaft in opposite directions to move the double clutch member into engagement with each of the beveled pinions.

2. In a reversing gearing for a straw tube or the like having a wheel forming the pivotal support thereof, a bracket plate mounted adjacent to said wheel, a drive shaft journaled in said plate, a worm upon the drive shaft, a beveled gear operatively connected to said wheel and journaled in the bracket plate, 80 spaced bearing arms upon the bracket plate, a tubular shaft located at right angles to the axis of said beveled gear, and journaled in said bearing arms, a worm wheel upon said tubular shaft meshing with said worm, a pair of beveled pinions loosely mounted upon said tubular shaft and meshing with said beveled gear, a solid shaft slidably mounted within the tubular shaft, said tubular shaft being slotted, a double clutch member slidably 90 mounted upon the tubular shaft, a radial pin connecting the solid shaft and double clutch member in one direction, spaced collars upon the solid shaft, a trip lever arranged to engage each of said collars, pins upon the wheel for alternately throwing the trip lever into engagement with each collar for sliding the solid shaft in opposite directions to move the double clutch member into engagement with each of the beveled pinions and spring 95 means upon the bracket plate, for quickly throwing the trip lever to reverse position when engaged by one of said pins and for holding the trip lever in each position.

SYDNEY G. MITCHINSON.
